The ornamental design for a slatted top hose box, as shown and described.

DESCRIPTION

FIG. 1 is an isometric view of the slatted top hose box;
FIG. 2 is another isometric view of the slatted top hose box;
FIG. 3 is a front side view of the slatted top hose box;
FIG. 4 is a back side view of the slatted top hose box;
FIG. 5 is a top view of the slatted top hose box;
FIG. 6 is a bottom view of the slatted top hose box;
FIG. 7 is a left side view of the slatted top hose box; and,
FIG. 8 is a right side view of the slatted top hose box.
The broken lines in the drawings depict environmental subject matter only and form no part of the claimed design.
